UNITED STATES PATENT OFFICE.

CARL C. THOMAS, OF MADISON, WISCONSIN.

METER.

1,364,920.

Specification of Letters Patent. Patented May 27, 1919.

Application filed December 27, 1910. Serial No. 599,456.

To all whom it may concern:

Be it known that I, CARL C. THOMAS, a citizen of the United States of America, and a resident of Madison, in the county of Dane and State of Wisconsin, have invented a certain new and useful Meter, of which the following is a specification.

The invention relates to meters.

It relates particularly to thermal fluid meters such as set forth in the patent to Carl C. Thomas, No. 946,886, though it is not limited to said meter. Meters of this type measure the flow of fluids by means of thermal or thermo-dynamic effects. Heat is imparted to the flowing fluid at a determinable rate and the effect of the imparted heat on the fluid is measured to determine the rate of flow.

When the steam or gas to be measured is wet, the meter must be provided with means for drying the gas in order to attain accurate results according to the method above referred to.

One of the objects of the present invention is to provide a meter with means for drying wet steam and gas prior to measuring the same.

Another object is to provide a meter with means for separating the moisture from the wet steam and gas and for heating the gas before it is measured.

A further object is to provide a simple, efficient and economical apparatus for accomplishing the above mentioned results.

Other objects and advantages of the invention will hereinafter appear.

The accompanying drawings illustrate an embodiment of the invention.

In said drawings:

Figure 1 is a longitudinal, sectional view of an improved meter having drying means associated therewith, the measuring means being constructed in accordance with my United States Letters Patent No. 1,043,983.

Fig. 2 shows a detail transverse section of the deflecting and moisture-collecting plates, and the inner casing to which same are connected, the section being taken on the inclined section line $x-x$ of Fig. 1;

Fig. 3 is a fragmentary longitudinal sectional view of a portion of a drier, illustrating a modified construction of deflecting and moisture-collecting plates;

Fig. 4 shows a front elevation of such plates; and

Fig. 5 shows a fragmentary section of the drier illustrating an alternative heater construction.

When the steam or gas to be measured contains moisture, some of the heat supplied by the heating unit of the measuring means, such as set forth in Patent No. 946,886, is used in converting the moisture into vapor or steam. This introduces inaccuracies and accordingly means must be provided for insuring that the gas flowing through the measuring means is dry.

When steam or gas flows along a pipe together with water, a large portion of the water may be, and generally is, found flowing along the inner surface of the pipe. The space between outer casing 1 and inner casing 5 serves to intercept such water. The water which is carried mechanically suspended in the steam or gas is driven down the inclined corrugations in plates 6, which thus provide for a continuous flow of the water in almost its original direction of flow, thus avoiding spattering and re-mixing with the gas.

The meter herein described has means associated therewith for drying the steam and gas in which as much as possible of the contained water is thrown out of the steam or gas mechanically, and then the partly dried steam or gas is subjected to the action of heating means, whereby such steam or gas passes from the drier in dry condition, and, in the case of steam, in a slightly superheated condition, while in the case of gas the water vapor still contained in such gas is in the form of slightly superheated steam. The specific heats of superheated steam and of most gases which are to be metered are so nearly equal and the proportion of water remaining after the mechanical separation is so small, that it is not necessary ordinarily to know the proportion of water to gas in the gas which finally issues.

Referring first to Figs. 1 and 2, 1 designates the main casing of the drier, 2 a separating chamber therein and 3 a drying chamber therein; 4 designates a water collecting chamber into which the water separated from the gas or steam drains and from which such water may be drawn off at intervals. 5 designates an inner casing, within chamber 2, the inlet end of which has an oblique mouth, as shown, and in front of this mouth are located deflecting

and moisture-collecting plates 6, 6. A flange 7, preferably inclined slightly downward as shown, covers the greater portion of the water collecting chamber 4, thereby preventing the steam or gas passing through the device from sweeping over the surface of the water in this chamber 4, while permitting water which trickles down the collecting plates 6, to pass into said chamber. The mouth 8 of the collecting chamber is preferably just beyond the end of these collecting plates. The inner casing 5 is preferably somewhat smaller than the internal diameter of the casing 1, as shown, so that said inner casing is jacketed by the steam or gas passing through the apparatus, and so is maintained at about the mean temperature of such steam or gas, and does not add to the free moisture in the steam or gas by condensation of moisture upon its walls.

Within the drying chamber 3 various drying means may be provided, but I prefer to employ a series of pipes 9 through which steam or superheated water may be passed, *i. e.*, water at a temperature above 212° F. For this purpose I have shown, at the upper and lower ends of chamber 3, tube sheets 10 into which the said tubes 9 fit, these tube sheets being covered by bonnets 11 inclosing between themselves and the tube sheets, chambers 12. A pipe 13 serves to supply steam or superheated water to the upper chamber 12, and a pipe 14 serves to carry away steam or water from the lower chamber 12. In the construction shown in Fig. 1, the lower bonnet 11 and the lower tube sheet 10 are within the casing; that is to say, they are located within a cylindrical pocket 15, in the lower portion of the casing, and are free to move up and down therein a short distance to allow free expansion and contraction of the tubes 9, the pipe 14 passing through a gland 15'. But this refinement in construction is not always necessary, and in Fig. 6 I illustrate a construction wherein the lower bonnet, here designated by reference numeral 11^a, is outside of the casing.

In Fig. 2 I illustrate one desirable construction of the moisture-collecting plates 6. According to this construction the said plates are corrugated and are arranged face to face with the corrugations mis-matching, the said plates being perforated along the crests of their corrugations. In the alternative construction shown in Fig. 3, the collecting plates, here designated by numerals 6^a, are approximately flat, but are perforated, burs 6^b being pressed out from the plates during the stamping of the perforations therein; which burs help to collect the moisture into drops of sufficient size so that, when such drops fall, they may pass

through the stream of gas or steam, without being caught up thereby. In both constructions the perforations of the plates are staggered with respect to each other, so that the steam or gas must follow a tortuous course in passing into the inner casing 5, as a result of which the bulk of its contained moisture will be thrown against the surface of the collecting plates and will trickle down the surfaces of said plates, collecting into drops thereon, and thence falling into the collecting chamber 4.

The measuring means, shown at the right of Fig. 1, comprises a main conduit 16 containing resistance conductors 17 and 17' of two electric thermometers, and containing also heating coils 18. The meter also has a by-pass passage 19 and valves 20 whereby the steam or gas may be by-passed around the thermometers and heating coils of the meter, or may be passed through the thermometer coils and heating coils, as desired, it being unnecessary in most cases to meter the flow continuously, measurement at reasonably frequent intervals being all that is required ordinarily.

In the operation of the meter the steam or gas enters the chamber 2 at the left hand end of Fig. 1, and, passing through the perforations of the collecting plates 6, (or 6^a, Fig. 3) parts with the greater portion of its moisture, such moisture collecting on the surfaces of said plates and trickling down into the collecting chamber 4. The nearly dried steam or gas is then subjected to the action of the heating pipes 9, whereby any remaining free moisture is evaporated, after which such dried steam or gas passes through the measuring means.

It will be understood that the steam or superheated water supplied to these pipes 9 is supplied at a temperature higher than that of the steam or gas entering the drier. It will be observed that the action of the drier is, or may be, continuous, whether the metering is continuous or not. The drier therefore serves, in the case of steam, as an efficient means for supplying saturated or even superheated steam.

It will thus be seen that a meter is provided having means associated therewith for insuring that the steam or gas to be measured is dry before entering the chamber containing the measuring means. The drying and heating means is simple, economical and efficient. It is combined with a measuring means and is a further development in the art of measuring the flow of steam or other gases and vapors by imparting heat thereto and determining the effect of the heat upon the flowing gas.

It should be understood that the structure shown is for purposes of illustration only and that other structures may be devised

which embody the invention and which come within the spirit and scope of the appended claims.

What I claim is:—

- 5 1. A fluid meter for measuring wet fluids, comprising means for separating part of the moisture from a stream of the fluid being measured, means for heating the fluid to further dry the same, means for imparting
- 10 10. heat to said dry fluid at a known rate, and means for determining the effect of said imparted heat whereby the rate of flow of fluid is determined.
- 15 2. A fluid meter for measuring wet fluids, comprising means for separating the moisture from a stream of the fluid being measured to dry the same, means for imparting heat to said dry fluid at a known rate, and means for determining the effect of said imparted heat on the fluid whereby the rate of flow of fluid is determined.
- 20 3. A fluid meter for measuring wet fluids comprising means for heating a stream of the fluid being measured to dry the same, means for imparting heat to the dry fluid at a known rate, and means for determining the effect of said imparted heat whereby the rate of flow of fluid is determined.
- 25 4. The combination with a fluid meter for measuring the flow of fluids by thermal means of means for drying the fluid entering the meter.
- 30 5. A meter for measuring the flow of fluids comprising means for drying the stream of fluid being measured, and thermal means for measuring the flow of dry fluid.
- 35 6. A meter for measuring the flow of fluids comprising means for heating the stream of fluid being measured to dry the

same and thermal means for measuring the flow of dry fluid.

7. A meter for measuring the flow of fluids comprising means for separating moisture from the stream of fluid being measured, means for heating the fluid to dry the same, and thermal means for measuring the flow of dry fluid.

8. A meter for measuring the flow of fluids comprising means for drying the stream of fluid being measured, and means for measuring the flow of dry fluids comprising electric heating means for heating the dry fluid and temperature measuring means for measuring the temperature rise thereof.

9. A meter for measuring the flow of fluids comprising means for heating the stream of fluid being measured to dry the same, means for imparting heat to the dry fluid, and means for determining the effect of the heat transfer between the fluid and the second heating means to measure the rate of flow.

10. A meter for measuring fluids comprising means for heating a stream of the fluid to dry the same, electric heating means for imparting heat to the dry fluid, and means for determining the effect of the heat transfer between the electric heating means and the fluid to determine the rate of flow.

In testimony whereof I have signed this specification in the presence of two subscribing witnesses.

CARL C. THOMAS.
